CENTRIFUGAL ROCK CRUSHER

Original Filed April 22, 1929 2 Sheets-Sheet 2

UNITED STATES PATENT OFFICE

ALVAH D. HADSEL, OF SAN FRANCISCO, CALIFORNIA

CENTRIFUGAL ROCK CRUSHER

Application filed April 22, 1929, Serial No. 357,190. Renewed March 15, 1932.

My invention relates to improvements in centrifugal rock crushers, and it consists in the combinations, constructions, and arrangements hereinafter described and claimed.

5 An object of my invention is to provide a centrifugal rock crusher which is continuous in operation and which makes use of a rotating rock-throwing member for causing rocks to be thrown against breaker blocks that are disposed circumferentially about the rock-throwing member. The angle of each breaker block with respect to the rock-throwing member is such as to cause the rocks to hit the blocks at right angles to the planes 10 of the blocks. This construction not only utilizes all of the force in breaking the rocks, but tends to do away with the abrasive action of the rocks upon the blocks caused by the rocks striking the blocks a glancing blow.

15 20 The wearing away of the blocks is materially decreased by this arrangement.

I have found that heavy blocks of iron chilled on the face receiving the blows of the rocks forms the best means for withstanding the wear of a continuous stream of rocks striking them. The blocks are suspended from their tops by adjustable hooks so that the blocks may be changed in position as certain portions of their faces become worn.

25 30 In this way the life of each block is materially increased.

The entire supporting of the blocks at their upper edges provides a clear space beneath the blocks for receiving the crushed rock.

35 40 If the blocks were supported at their bottoms, the pockets thus formed would quickly be filled with crushed rock and would interfere with the efficient operation of the device.

I have found that the rock-throwing member is subject to great wear unless provision is made for handling the rocks. The thrower is provided with a number of receptacles or pockets that receive and hold some of the rock. This rock acts as a shock absorber for additional rock passing through the thrower and prevents this latter rock from wearing away the sides of the thrower.

45 50 Other objects and advantages will appear as the specification proceeds, and the novel

features will be particularly pointed out in the appended claims.

My invention is illustrated in the accompanying drawings in which:

Figure 1 is a top plan view of the device, 55 portions being broken away for clarity;

Figure 2 is a vertical section through the device, certain parts being shown in elevation;

Figure 3 shows a motor driven rock-throwing member;

Figure 4 is a section along the line 4-4 of Figure 3; and

Figure 5 shows how the blocks are worn by the rock. 65

In carrying out my invention, I provide a housing 1 which in the present form of the device is octagonal in cross section. This housing is covered by a roof 2 supported by radially-extending I-beams 3. A central rock chute 4 extends through the roof 2, and a pile of rock 5 is gradually fed into the chute. 70

The chute drops the rock into the center of a runner indicated generally at 6 (see Figure 4). This runner has bottom and top walls 7, 75 side walls 8, and end walls 9. The walls 8 and 9 do not extend throughout the entire lengths and sides of the runner, but terminate short of certain of the ends for providing openings 11 through which the rock passes when it is 80 thrown from the runner.

The runner 6 is rotated at approximately 450 R. P. M. which is at a sufficient speed to cause the rock to leave the ends of the runner at a tangent. I have found that the rotation 85 of the runner will cause the rock to dig into the side walls 8 at two places, one near the center of the runner as indicated by the letter X and the other near the end of the runner as indicated by the letter Y. I have provided 90 two transversely-extending partitions 10 for forming pockets A and B. Rock is received in these pockets and is kept there. Any additional rock will strike the rock already retained in the pocket and will wear away this rock instead of the side walls 8.

The end walls 9 cooperate with the side walls 8 for providing two other pockets C and D. Rock is held stationary in these pockets and will act in the same manner as the

rock in the pockets A and B for preventing a wearing action upon the side walls 8.

The partitions 10 carry removable plates 12. These plates are subject to wear as the rock passes through the runner and may be changed from time to time. The end walls 9 also carry plates 13 that are removably secured to the end walls by bolts 14. The plates 13 have rounded ends 15 provided with concave edges 16. The rock in leaving the runner is guided centrally between the top and bottom plates 7 by the concave edges 16.

The rock, as already stated, leaves the runner in a path that is tangent to the circular path taken by the ends of the runner. I have arranged breaker blocks 17 (see Figure 1) circumferentially about the runner 6 and at such angles as to be struck by the rock at right angles to the inner faces 18 of the blocks. The blocks are large and heavy, being practically twenty-two inches square by four inches deep, and are made of iron with their faces 18 chilled to a depth of approximately an inch and a half. Each block weighs in the neighborhood of six hundred pounds, and therefore will be practically stationary when struck by the rock.

Each block 17 is provided with four recesses 19 and has openings 20 leading from the recesses for receiving hooks 21 (see Figure 2). The hooks are passed through the openings 22 in the roof 2 (see Figure 1), and have their ends threaded for adjustably receiving nuts 23 (see Figure 2). The blocks hang downwardly at an angle for directing rock that strikes them downwardly.

A larger opening 24 (see Figure 1) is disposed between each set of openings 22. A rope is passed down through this opening for raising the block into a new position, whereupon the nuts 23 may be adjusted for holding the block in its new position.

In Figure 5 I show four positions of one block 17 with its face 18 facing toward the front. When the block is new, it will be worn along the area E enclosed by the dotted lines. The block 17 is then raised for causing a new area F to be worn. A third raising will present the area G, which will be likewise worn.

After this the block is turned through ninety degrees so as to dispose the areas E, F and G at the bottom of the block. The area H will now be worn, and after two adjustments the areas J and K will be worn. The block is then turned through another ninety degrees, which will wear away a new area L after the three adjustments have been made. One more swinging of the block will present the area M. When this is worn away, the block is discarded and a new one takes its place. The areas will overlap each other, and in this way practically the entire surface 18 of the block is used.

From the foregoing description of the va-

rious parts of the device, the operation thereof may be readily understood.

Rock is fed into the chute 4 and drops upon the runner 6. From here it is thrown against the blocks 17 in such a way that the rocks 70 will strike the faces 18 at right angles. The blocks 17 are so positioned as to cause all of the rock to strike some block. Figure 1 shows the blocks overlapping slightly.

The speed of the runner has been adjusted 75 so that the rock will strike the blocks at a certain velocity which is sufficient for breaking the rock into small pieces. The space beneath the blocks is free, and the crushed rock will build up sloping banks of rock 25. 80 This rock will feed down into an outlet chute 26 by gravity, and will be dropped upon a conveyor belt 27 that carries the rock to any place desired.

In Figures 1 and 2 I show the runner 6 as 85 being rotated by a shaft 28. The shaft in turn carries a pulley 29, and the pulley is rotated by a belt 30.

In Figure 3 I show the runner 6 as being rotated by a motor 31. In all other respects 90 the form of the device shown in Figure 3 is identical to the form described.

The machine is continuous in operation, and it is only necessary to change the positions of the blocks as certain portions of the 95 surfaces 18 become worn and then to remove the blocks from time to time as necessary.

Although I have shown several embodiments of my invention, it is to be understood that the same is susceptible of various changes, 100 and I reserve the right to employ such changes as may come within the scope of the invention as claimed.

I claim:

1. In a centrifugal rock crusher, a runner 105 for receiving rocks centrally and for discharging them peripherally, said runner having substantially parallel side walls with pockets formed therein for holding a layer of rock that will prevent other rock from 110 striking the walls, said pockets being formed by partitions and end walls.

2. A centrifugal rock crusher comprising a runner for receiving rocks and for throwing them tangentially therefrom, a plurality of substantially flat-faced blocks arranged circumferentially around said runner and being supported from their tops, said blocks partially overlapping each other and being inclined slightly for directing the rocks downwardly. 120

3. In a centrifugal rock crusher, a rotatable runner for receiving rock centrally and for throwing it tangentially from the ends of the runner, a plurality of breaker blocks arranged circumferentially around said runner and being positioned for receiving the impact of all of the rocks and being slightly inclined for directing the broken rocks downwardly, and adjustable means for supporting all of said blocks solely at their tops. 125

4. In a centrifugal rock crusher, a rotatable runner for receiving rock centrally and for throwing it tangentially from the ends of the runner, a plurality of breaker blocks arranged circumferentially around said runner and being positioned for receiving the impact of all of the rocks and being slightly inclined for directing the broken rocks downwardly, and adjustable means for supporting all of said blocks solely at their tops, said blocks being movable into four different positions on said means. 70
5. In a rock crushing machine of the character described, a breaker block means for discharging rocks thereagainst with sufficient force to break the rocks into particles upon impact, and means for supporting said block entirely from the top with freedom of swinging motion, said block normally being held stationary by its own weight when the rocks contact therewith. 75
6. In a rock crusher of the character described, a revolvably mounted runner having substantially parallel walls, means for feeding rocks thereinto, means for revolving the runner whereby the rocks are discharged from the ends of the runner, and stops formed adjacent to the trailing wall of the runner allowing a number of rocks to lodge therebehind so as to serve as a protecting cushion for the trailing wall. 80
7. In a rock crusher of the character described, a channel-shaped revolvably mounted runner, means for axially feeding rocks thereinto, means for revolving the runner whereby the rocks are discharged from the ends of the runner, and stops secured to the parallel walls of the runner allowing a number of rocks to lodge therebehind so as to serve as a protecting cushion for the trailing walls. 85
8. In a rock crusher of the character described, a channel-shaped revolvably mounted runner, means for feeding rocks thereinto, means for revolving the runner whereby the rocks are discharged from the ends of the runner, and stops secured to the parallel walls of the runner allowing a number of rocks to lodge therebehind so as to serve as a protecting cushion for the trailing walls. 90
9. In a centrifugal rock crusher, a rotatable runner for receiving rocks centrally and for throwing them tangentially from the ends of the runner, and a plurality of breaker blocks arranged circumferentially around said runner and being positioned for receiving the impact of all of the rocks and being slightly inclined with respect to a vertical plane for directing the broken rocks downwardly. 95
10. In a centrifugal rock crusher, a rotatable runner for receiving rock and for throwing it tangentially from the ends of the runner, said runner including obstructions extending at substantially right angles to the 100
11. In a rock crusher of the character described, a channel-shaped runner having substantially parallel walls, means for feeding rocks into the channel, means for revolving the runner whereby the rocks are discharged from the ends of the runner, and stops secured to the parallel walls of the runner allowing a number of rocks to lodge therebehind so as to serve as a protecting cushion for the trailing walls. 105
12. In a rock crusher of the character described, a channel-shaped runner having substantially parallel walls, means for feeding rocks into the channel, means for revolving the runner whereby the rocks are discharged from the ends of the runner, and stops secured to the parallel walls of the runner allowing a number of rocks to lodge therebehind so as to serve as a protecting cushion for the trailing walls. 110
13. In a rock crusher of the character described, a channel-shaped runner having substantially parallel walls, means for feeding rocks into the channel, means for revolving the runner whereby the rocks are discharged from the ends of the runner, and stops secured to the parallel walls of the runner allowing a number of rocks to lodge therebehind so as to serve as a protecting cushion for the trailing walls. 115
14. In a centrifugal rock crusher, a rotatable runner for receiving rock and for throwing it tangentially from the ends of the runner, said runner including obstructions extending at substantially right angles to the 120
15. In a centrifugal rock crusher, a rotatable runner for receiving rock and for throwing it tangentially from the ends of the runner, said runner including obstructions extending at substantially right angles to the 125
16. In a centrifugal rock crusher, a rotatable runner for receiving rock and for throwing it tangentially from the ends of the runner, said runner including obstructions extending at substantially right angles to the 130
